(57) **CLAIM**

The ornamental design for the display screen or portion thereof with animated graphical user interface for symptom tracking of COVID-19, as shown and described.

DESCRIPTION

FIG. 1 is a front view of first image in the sequence of a display screen or portion thereof with animated graphical user interface for symptom tracking of COVID-19 showing our new design;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the animated image sequentially transitions between the images shown in FIGS. 1-8. The process or period in which one image transitions to another image forms no part of the claimed design.

The dashed broken line showing of a display screen or portion thereof is included for the purpose of illustrating portions of the article and forms no part of the claimed design.

1 Claim, 6 Drawing Sheets
